Des. 236,256
Patented Aug. 12, 1975

236,256

FOLDING SLED

Werner Hellman, 716 12th St.,
Baraboo, Wis. 53913

Filed Sept. 24, 1973, Ser. No. 400,333

Term of patent 14 years

Int. Cl. D12—14

U.S. Cl. D12—11

Fig. 3

Fig. 4

FIG. 1 is a perspective view of a folding sled showing my new design in its open position;

FIG. 2 is a perspective view thereof in its closed position;

FIG. 3 is a top plan view of FIG. 1;

FIG. 4 is a side elevational view of FIG. 1, it being understood that the opposite side is a mirror image thereof;

FIG. 5 is a bottom plan view of FIG. 1;

FIG. 6 is a front elevational view of FIG. 1; and

FIG. 7 is a rear elevational view of FIG. 1.

I claim:

The ornamental design for a folding sled, as shown.
